incally.

UNITED STATES PATENT OFFICE.

WILLIAM B. STEARNS, OF MILTON, MASSACHUSETTS.

ELECTRICAL DISTRIBUTOR.

Application filed April 25, 1922. Serial No. 556,364.

To all whom it may concern:

Be it known that I, WILLIAM B. STEARNS, a citizen of the United States of America, and resident of Milton, in the county of Norfolk and State of Massachusetts, have invented new and useful Improvements in Electrical Distributors, of which the following is a specification.

This invention relates to electrical distributors of the type used to control the ignition of internal combustion engines, commonly called commutators or timers, but certain of the features of the invention are capable of general application.

10 Most distributors or timers in common use have a spring-pressed contact arm arranged to follow a closed circular path and wipe across spaced contacts in the distributor housing. Such devices have several serious defects. The spring which forces the contact arm outwardly frequently becomes weakened or broken resulting in irregular operation or complete failure. Wear develops irregularities in the path followed by 20 the rotating arm such that the latter at times jumps over the contacts. Sparking between the contacts frequently occurs resulting in burning and fouling of the contact members and sometimes in fires if gaso- 25 line or other highly inflammable vapors are present.

Objects of the invention are to provide a device of the class described which will operate efficiently for an indefinite period 30 without appreciable wear, to eliminate parts which may be easily weakened or broken such as springs and other delicate parts, to prevent sparking between the contacts and fouling thereof and in general to simplify 35 and improve devices of the character described and to make them more efficient and satisfactory in operation.

The invention comprises relatively movable parts having opposed circuit closing 40 elements arranged to register with each other in successive positions of the parts, at least one of the elements comprising electrical conducting fluid trapped in a recess.

For the purpose of illustration species

of the genus constituting the invention are shown in the accompanying drawings, in which:

Fig. 1 is a side elevation with parts of the distributor in section;

Fig. 2 is a view similar to Fig. 1 showing a modification;

Fig. 3 is a section on the line 3—3 of Fig. 1.

The embodiment of the invention shown for the purpose of illustration comprises an electrical distributor or timer adapted for use in controlling the ignition of an internal combustion engine. The particular type of commutator here shown is suitable for a four-cylinder engine. As shown, the distributor comprises a shaft 4 supported for rotation in bearings 5 on brackets 6 attached to any convenient portion of the engine frame. Any suitable means may be provided for rotating shaft 4, such as a gear wheel or pulley 7 operated by the engine through a suitable connection.

Surrounding shaft 4 (which is preferably of metal) and fast thereon for rotation therewith, as by pins 8, is a sleeve 9 of insulating material such as fibre or hard rubber which has a close sliding fit with a stationary casing 10 also of insulating material such as fibre or hard rubber. Upon one side of the casing 10 are projections or bosses 11 upon which terminals 12 are adapted to be made fast. The electrical contacts in the casing 10 to which terminals 12 are connected are preferably formed by making an opening 13 in each of the bosses 11 extending from the exterior thereof to the opening for the rotor which comprises parts 4 and 9. Terminals 12 are fast in openings 13 in any suitable manner as by the screw threaded attachment shown there- 90 by closing one end of each opening 13 which thereupon becomes a recess opening toward the rotor portion of the device.

The rotor portion of the distributor, comprising shaft 4 and sleeve 9, is provided with recesses 14 spaced longitudinally and circumferentially thereof. In the form shown each recess is at an angle of 90° to

the next, and each recess 14 is in line with a corresponding recess 13 in the stator casting 10, so that each quarter revolution of shaft 4 will bring one of the recesses 14 into registration with one of the recesses 13. Recesses 13 and 14 are filled with a suitable electrical conducting fluid such as mercury. By reason of the close fit between the sleeve 9 and housing 10, the mercury in these recesses is trapped therein, and no loss or leakage thereof occurs.

In Fig. 2 a modified structure is shown, the general arrangement being identical with Fig. 1, but instead of having recesses in the rotor filled with mercury metal plugs 14' are employed. As shown these plugs are round instead of oval, as are the openings 14 in Fig. 1, and they have a tight pressed fit in both shaft 4 and sleeve 9.

It will be understood that the shaft 4 constitutes the common return of the branched circuit and that this return may lead to ground or, by insulating the shaft of the machine from ground, to the battery.

It will be clear from the above that the complicated mechanisms of the distributors or timers in common use have been avoided and that good contact will be secured through the mercury contacts shown in Fig.

1 or through the metal and mercury contacts shown in Fig. 2. The use of mercury has the peculiar advantage that impurities and the scum produced by oxidation rise to the top of the pocket of mercury so that the

metal is free from impurities as the parts of contact in both of the modifications shown whereby a good electrical connection is consistently produced. It will furthermore be evident that the sparking between contacts frequent in distributors of the ordinary type is entirely avoided due to the close fit of sleeve 9 in housing 10.

I claim:

1. An electrical distributor having relatively movable non-conducting parts in contact with each other, said parts having recesses adapted to be brought into registration, and electrical conducting fluid in said recesses.

2. An electrical distributor having relatively movable non-conducting parts in sliding contact with each other, circuit closing members on said parts arranged to register in certain positions thereof, the circuit closing members on one part comprising electrical conducting fluid trapped in recesses in said part by the sliding engagement of the parts.

3. An electrical distributor having a rotating part and a stationary part in sliding contact therewith, one of said parts being formed from non-conducting material, circuit closing members on both said parts arranged to register in certain positions, one of said members comprising electrical con-

ducting fluid trapped in a recess in one of said parts by their sliding contact.

4. An electrical distributor comprising a rotating part and a stationary part enclosing said rotating part, said rotating part having a core of conducting material and an outer layer of insulating material arranged for sliding contact with said stationary part, said layer having openings therethrough registering in certain positions of said rotating part with contacts on said stationary part, and a liquid conducting medium in said openings in contact with said core for cooperation with the contacts on said stationary part.

5. An electrical distributor comprising a rotating part and a stationary part enclosing said rotating part, said rotating part having a core of conducting material and an outer layer of insulating material arranged for sliding contact with said stationary part, said layer having openings spaced longitudinally and circumferentially thereof, said openings registering in certain positions of said rotating part with contacts on said stationary part, and a liquid conducting medium in said openings in contact with said core for cooperation with the contacts on said stationary part.

6. An electrical distributor comprising a stationary part, a rotatable part within said stationary part and having an outer face in sliding contact with a complementary face on said stationary part, means in said parts for successively closing an electric circuit comprising spaced contact members on said parts, said members on one of said parts being spaced circumferentially as well as longitudinally.

7. An electrical distributor comprising a stationary part, a rotatable part within said stationary part and having an outer face in sliding contact with a complementary face on said stationary part, means in said parts for successively closing an electric circuit comprising spaced contact members in the form of electrical conducting fluid trapped in openings in the opposed faces of said parts and adapted to be in registration in certain positions of said parts.

8. An electrical distributor comprising a stationary part, a rotatable part within said stationary part and having an outer face in sliding contact with a complementary face on said stationary part, means in said parts for successively closing an electric circuit comprising spaced contact members in the form of electrical conducting fluid trapped in openings in the opposed faces of said parts and adapted to be in registration in certain positions of said parts, said members on one of said parts being spaced circumferentially as well as longitudinally thereof.

9. An electrical distributor having rela-

tively movable parts in contact with each other, said parts having recesses adapted to be brought into registration, and mercury in said recesses forming electrical contacts.

5 10. An electrical distributor having relatively movable parts in contact with each other, circuit closing members on said parts arranged to register in certain positions of said parts, the circuit closing members on 10 one part comprising mercury trapped in recesses in said part.

11. An electrical distributor comprising a stationary part, a rotatable part within said stationary part and having an outer face 15 in sliding contact with a complementary face on said stationary part, means in said parts for successively closing an electric circuit comprising spaced contact members in the form of mercury trapped in openings in the 20 opposed faces of said parts and adapted to be in registration in certain positions of said parts.

12. An electrical distributor having a cylindrical rotatable part, a stationary part 25 forming a closely fitting housing for said rotatable part, said stationary part having openings therein, the outer ends of said openings being closed by connector terminals and the inner ends by said rotatable 30 part, and electrical conducting fluid filling

said openings to form inwardly disposed contact members.

13. An electrical distributor having a cylindrical rotatable part, a stationary part, forming a closely fitting housing for said rotatable part, said stationary part having openings therein, the outer ends of said openings being closed by connector terminals and the inner ends by said rotatable part, and mercury filling said openings to 35 40 form inwardly disposed contact members.

14. An electrical switch comprising a non-conducting member arranged for sliding contact with a second non-conducting member, said members having opposed recesses arranged to register in a certain position of said parts, and electrical conducting fluid in said recesses for closing a circuit when 45 said recesses are in registration.

15. An electrical switch comprising a non-conducting member arranged for sliding contact with a second non-conducting member, said members having opposed recesses therein arranged to register in a certain position of said parts, and mercury in 50 55 said recesses for closing a circuit when said recesses are in registration.

Signed by me at Massachusetts this 15th day of April, 1922.

WILLIAM B. STEARNS.
